UNITED STATES PATENT OFFICE

164,787

COMBINATION WASHBASIN AND UTILITY
CABINET

Bernard F. McMahon, Clayton, Mo.

Application April 9, 1951, Serial No. 14,760

Term of patent 14 years

(Cl. D4—2)

To all whom it may concern:

Be it known that I, Bernard F. McMahon, a citizen of the United States, residing at Clayton, State of Missouri, have invented a new, original, and ornamental Design for Combination Wash-basin and Utility Cabinet, of which the following is a specification, reference being had to the accompanying drawing, forming a part thereof.

Fig. 1 is a plan view of a combination wash-basin and utility cabinet, showing my new design, with the hinged cover of the utility cabinet in a closed position;

Fig. 2 is a front elevational view thereof;

Fig. 3 is a plan view thereof, with the hinged or pivotally mounted cover of the utility cabinet in a raised position;

Fig. 4 is a front elevational view thereof, with the hinged or pivotally mounted cover of the utility cabinet in a raised position;

Fig. 5 is a rear elevational view thereof, with the hinged or pivotally mounted cover of the utility cabinet in a raised position;

Fig. 6 is an end elevational view thereof, with the cover of the utility cabinet in a closed position, the opposite side being the same as that illustrated; and

Fig. 7 is a vertical, central, longitudinal cross-sectional view thereof, with the cover of the utility cabinet in a closed position.

The characteristic features of my design reside in the portions shown in full lines, the portions shown in broken lines being only for illustration purposes.

I claim:

The ornamental design for a combination washbasin and utility cabinet, substantially as shown and described.

BERNARD F. McMAHON.
